COVER FOR ROTARY BRUSH SWEEPERS

Henry O. Beyer and Frank M. Bauman,
Morton, Ill.

Application March 8, 1948, Serial No. 13,618

6 Claims. (Cl. 15—83)

1

This invention relates to a cover for a rotary brush sweeper and more particularly to a cover for a rotary brush sweeper, which is propelled by a tractor or similar vehicle, and has for its primary object to impound dirt or other foreign particles, so as to enable the sweeper to sweep the dirt, rubbish or other particles from the street and, at the same time, to collect the dirt and rubbish and convey it to a suitable depositing zone.

Another object of this invention is to retain or confine, adjacent to the rotary brush, any dust currents which will be created by the rotating movement of the brush in contact with the surface of a street, highway or the like.

Another object of this invention is to enable a sweeper, such as a street sweeper or the like, to serve in a dual capacity, as a sweeper and as a dirt rubbish collecting device, so that the dirt and rubbish swept up by the sweeper is retained within a suitable cover or housing for the sweeper and is prevented from seeping out to form windrows, along the path of the sweeper.

Another object of this invention is to provide means whereby the cover overlying the sweeper and retaining the dirt or rubbish therein, is lifted from engagement with the ground to allow the dirt or rubbish therein, to be freed and piled in a suitable depositing area.

A meritorious feature of this invention resides in the provision of a hood, overlying the upper portion of a rotary sweeper, with a flexible depending skirt positioned in the front of the sweeper and engaging the ground and a flexible shield depending from one end of the hood to a point in engagement with the ground, so that with an open end of the hood positioned in a leading angle, the dirt or rubbish swept up by the sweeper is impounded or retained within the hood and depending skirt.

These and ancillary objects and other meritorious features are attained by this invention, a preferred embodiment of which is set forth in the following description and illustrated in the accompanying drawings, wherein:

Figure 1 is a perspective view of a tractor propelled rotary sweeper, illustrating a cover positioned over the rotary sweeper, the cover being constructed in accordance with the principles of this invention;

Figure 2 is a top plan view of this invention;

Figure 3 is a side elevational view, showing the side cover, secured at one end of the rotary sweeper;

Figure 4 is a front elevational view of the cover

comprising an upper hood construction and a depending flexible skirt;

Figure 5 is a vertical sectional view taken substantially on the plane of line 5—5 of Figure 4;

Figure 6 is an enlarged sectional view taken substantially on the plane of line 6—6 of Figure 3.

Referring now more particularly to the drawings, wherein similar characters of reference designate corresponding parts throughout, and with particular reference to Figure 1 thereof, there is shown a tractor 10 of conventional structure, in front of which is positioned and propelled thereby, a rotary sweeper 12, with a cover 14 enclosing the sweeper, the cover 14 being constructed according to the principles of this invention.

The cover 14 for the rotary sweeper comprises a hood 16, semi-circular in cross section and adapted to overlie the upper portion of the rotary sweeper, said hood having depending first and second semi-circular sides 18, 18' disposed at closed and open ends of the cover 14, respectively.

Suitably secured to the terminating portion of the front of the hood 16 is a flexible rectangular plate 20, or skirt, closing the front of the cover 14 below the hood 16 and having one end in alignment with the open end of the cover, with the opposite end protruding or extending beyond the opposite closed end, as seen in Figure 1 of the drawings. The flexible plate 20, of any suitable material, such as leather belting or the like, is secured at its upper edge between the lower front edge of the hood 16 and an attaching bar 22 which is bolted through said plate to said hood by bolts 26 having nuts 27 thereon. One end of the attaching bar 22 and one end of said plate 20 extend outwardly beyond the end 18 of the hood 16 and the extending end of said plate 20 is attached to the extending end of said bar 22 by bolts 26'.

Suitable means are provided to retain the flexible plate 20 in vertical depending placement and to retain the same in ground engagement and preferably comprises a pair of weights of any suitable kind, such as, elongated bars 30 and 32, which are secured on either side of the depending edge of the flexible plate by means of conventional bolts 34 and nuts 36.

Attached to the lower diametrically straight edge of the hood end 18 on the outer surface thereof is a bar 38, with an upper edge of a flexible shield, 40, such as leather belting or the like, secured between the bar 38 and the end 18, by conventional means, such as securing bolts and

55

nuts 42. The lower edge of the flexible shield 40 extends angularly outwardly and terminates downwardly in secured placement by means of bolts 44 at the inner surface of a drag block 46. The drag block 46 may be composed of any suitable material, such as wood or the like, which is of a substantial weight, to retain the shield 40 in depending placement. Suitable means are provided to yieldingly urge the drag block 46 in engagement with the surface, street or the like and comprises a pair of extending bracket blocks 48 and 50, which protrude or extend outwardly of the side bar 38, the parallel attaching arms of the blocks being suitably secured to the side bar. The shield 40 and drag block 46 together with 15 end 18 of the hood 16 form the closed end of the cover 14.

Secured to the outer extended face of the blocks 48 and 50 by means of U-shaped bearing brackets 52 and 54, which are bolted to the block by means of bolts 56, are a pair of depending rods 58 and 60. The rods 58 and 60 are suitably threaded at their extremities, with one end of the rods being secured through the U-shaped brackets and retained in such seatment by means of the cooperating locking nuts 62 which are seated on the U-shaped brackets 54 and 52 respectively. The depending threaded ends of the rods 60 and 58 extend through suitable bores or openings vertically formed in the drag block 46, with suitable notches or openings 64 being formed in the bottom portion of the drag block 46 to house or accommodate locking nuts 66, which are threadedly received on the depending end of the rods. Suitably carried or received on the rods 58 and 60 between the U-shaped brackets 54 and 52 and seated on washer and locking nut assemblies 68, which are seated on the upper surface of the drag block 46, are a pair of resilient coil springs 70 and 72, which serve to yieldingly urge the drag block 46 into ground engagement.

Of course, an extending angle iron 74 is secured by means of bolts 76 to the lower face and inner side of the drag block 46 and serves to prevent wear and tear on the bottom of the drag block, which due to its weight and the urging of the springs 70 and 72 is maintained in constant placement on the surface of the ground.

Thus, it can be seen that when the open end of the hood, which is not provided with any depending ground engaging portion, is positioned so as to be forwardly placed relative to the drag block 46, and the brush is propelled or moved along the ground by the tractor or similar vehicle 10, the rotary brush 12 is suitably rotated and the dirt or other debris is swept up by the brush and suitably carried to the rearwardly situated and closed end 18 of the cover. It is to be apparent that the free end of the flexible front shield or plate 20 is suitably movable in and out of the hood while the opposite protruding end is retained in vertical placement by the abutment of the plate with the extending end of the drag block 46. As is conventional in sweepers of the type described, the brush rotates so that the ground engaging portion of the brush is moving relatively opposite to the ground. Thus, the dirt or debris which is moved by the rotary sweeper 12 to the drag block side of the cover is retained or impounded within the cover 14, by means of the side cover 40 in cooperation with the flexible front plate 20, which is rigidified at the extending end by the forward portion of the drag block.

Thus, as the sweeper is moved along on the ground by the tractor, the dirt or debris is retained within the cover 14 and is prevented from trickling or moving out of the cover and forming windrows along the side of the path of travel of the tractor or propelling vehicle. Suitable means may be provided for raising the cover 14 to release dirt and debris to form piles, but, such means not being claimed herein has not been illustrated nor described.

It is thus apparent that there is provided a cover for a rotary brush, which will prevent the movement of dust currents up to the operator's position on the pushing vehicle and which will retain the dirt or debris, so as to later deposit the debris in a selected depositing locale. Also, it is to be noted that the flexible plate 20 and the end shield 40 and the attaching and contiguous components of each may be utilized in association with a conventional hood or shield for a rotary or other type brush or sweeping attachment.

Since many other purposes and objectives of this invention will become apparent to those skilled in the art, upon a perusal of the foregoing description, in view of the accompanying drawings, it is to be understood that certain changes may be effected thereon, without a departure from the spirit of the invention and within the scope of the appended claims.

Having described the invention, what is claimed as new is:

1. A dirt retaining cover for a rotary brush comprising a hood adapted to overlie the upper portion of the brush and having a front edge and ends, a semi-rigid skirt secured to the front edge of the hood and adapted to depend therefrom in advance of the brush and having one end extended beyond the hood, ground engaging means secured to the lower edge of the skirt, an outwardly bowed flexible shield secured to and depending from one end of the hood, a drag block secured to the lower edge of the shield and abutting at its forward end against the extended end of the skirt to prevent rearward movement of said end of the skirt, resilient means for yieldingly retaining the block in ground engagement.

2. A dirt retaining cover for a rotary brush comprising a hood adapted to embrace the upper portion of the brush and having a front edge and ends, a semi-rigid skirt secured to the front edge of the hood and adapted to depend therefrom in advance of the brush, one end of said skirt being extended beyond one end of the hood, ground engaging means secured to the lower edge of the skirt, an outwardly bowed flexible shield secured to and depending from one end of the hood, a drag block secured to the lower edge of the shield and abutting at its forward end against the extended end of the skirt, supporting rods extending from said drag block, means on said end of the hood slidably mounting said rods for upward movement relative to the hood, and resilient means concentrically disposed on said rods for tensioning said rods against upward movement and yieldingly retaining said block in ground engagement.

3. A dirt retaining cover for a vehicle propelled rotary brush, said brush being disposed in advance of the vehicle and inclined relative to the axis of the vehicle, comprising a hood adapted to overlie the upper portion of the brush and having end walls and a front edge adapted to embrace the upper portion of the ends of the

brush, a semi-rigid skirt secured to the front edge of the hood and adapted to depend therefrom parallel with and in advance of the brush, ground engaging means carried by the lower edge of the skirt, one end of said skirt being extended beyond one of the end walls of the hood, a flexible shield secured to the lower edge of said last mentioned end wall, weight means secured to the lower edge of the shield, said last means abutting against the extended end of the skirt for preventing rearward movement of the end and resilient means for yieldingly retaining said means in ground engagement.

4. In combination with a vehicle propelled rotary brush, said brush being disposed in advance of the vehicle and inclined relative to the axis thereof, a dirt retaining cover for said brush comprising a hood overlying the upper portion of the brush and inclined in correspondence therewith and having depending end walls embracing the upper portion of the ends of the brush, said hood having a front edge, a semi-rigid skirt secured to and depending from the front edge of the hood and disposed parallel with and in advance of the brush, one end of the skirt extending beyond the rearwardly directed end wall of the hood, ground engaging means carried by the lower edge of the skirt and disposed co-extensive therewith, a flexible shield secured to the lower edge of the rearwardly directed end wall of the hood, a drag block secured to said shield, means for yieldingly urging said block in to engagement with the ground, said block having its forward end abutting against the extended end of the skirt to prevent rearward movement thereof.

5. The combination of claim 4, wherein said last named means includes a pair of vertically

reciprocable rods attached at their lower ends to the block, means carried by said rearwardly directed end wall of the hood for supporting said rods, and springs concentrically disposed about said rods between the block and supporting means.

6. The combination of claim 5, wherein said supporting means includes bracket members extending laterally from said rearwardly directed end wall of the hood and having vertical guide collars aligned with the block and adapted to slidably receive the rods.

HENRY O. BEYER.
